UNITED STATES PATENT OFFICE.

JOHN O. MCKEAN, OF WESTFIELD, MASSACHUSETTS, ASSIGNOR TO FOSTER MACHINE COMPANY, OF WESTFIELD, MASSACHUSETTS, A CORPORATION OF MASSACHUSETTS.

YARN-TENSION DEVICE.

Application filed November 27, 1926. Serial No. 151,144.

Yarn, in its passage through a tension device, such, for instance, as a tension device comprising a movable tension member and its support, wears away more or less rapidly the 5 yarn contact surface of the support, finally cutting a groove so deep as to cause the movable tension member to become inoperative by removing its pressure on the yarn. This wearing away of the yarn contact surface 10 of the support is particularly rapid when certain yarns are used such as jute and asbestos; or when yarn is used which is dirty or gritty or which is filled with size. The tension support, because of this wear on its 15 yarn contact surface, has had to be replaced frequently at a considerable expense.

The object of my invention is to provide a replaceable stationary member interposed between the movable tension member and its support for protecting the support from wear or to permit the further use of a support having a worn yarn contact surface, said replaceable stationary member being preferably made of a material which will resist 20 the wearing effect of the yarn to a much greater degree than the material of which the tension support can feasibly be made. My invention more particularly comprises a replaceable stationary plate inserted between a 25 gravity operated rotatable tension washer and the usual yarn contact surface of its support, said plate being provided with means such as a depending flange for preventing the yarn from being accidentally threaded 30 under the plate.

Practical embodiments of my invention are represented in the accompanying drawings, in which:

Fig. 1 represents in top plan a yarn tension device with one form of replaceable plate applied thereto.

Fig. 2 represents a side view of the same.

Fig. 3 represents a detail section taken in the plane of the line III—III of Fig. 1.

Figs. 4, 5 and 6 represent a second form 45 of replaceable plate in top plan, side elevation and transverse section respectively.

Figs. 7, 8 and 9 represent a third form of 50 replaceable plate in top plan, side elevation and transverse section respectively.

Figs. 10, 11 and 12 represent a fourth form 55 of replaceable plate in top plan, side elevation and transverse section.

The yarn tension device in connection with

which I have chosen to illustrate my invention is shown as comprising the tension head 1 which forms a support for a pair of gravity operated weighted tension washers 2 which are loosely mounted on pins 3 uprising from the usual yarn contact surface 4 of the support along which the yarn is drawn beneath the washers 2. The usual yarn guard 5 for preventing the washers from jumping off from their pins is pivoted to the support at 6. This support 1 may be provided with the usual leading-in guide 7 and tension equalizing bar 8.

To eliminate the wear upon the usual yarn contact surface of the support 1 by the passage of the yarn thereover between said surface and the rotatable washers, or to render further useful, supports having worn yarn contact surfaces, I provide a replaceable stationary plate 9, (preferably of hardened steel) which is inserted between the usual 70 yarn contact surface of the support and the tension washers. In the forms herein shown, this plate is provided with holes 10 for receiving the uprising pins 3, to properly position the plate on the yarn contact surface of the support and hold it stationary.

Means are provided on the plates 9 for preventing the accidental threading of the yarn underneath the plates, which means in Figures 1, 2 and 3 is shown as a single depending flange 11 extending from the leading-in end of the plate partway toward its rear end in close proximity to its adjacent side of the support. In Figures 4, 5 and 6, I have shown a second depending flange 12 extending from 80 the rear end of the plate partway toward its leading-in end. In Figures 7, 8 and 9 I have shown a single depending flange 13 extending the full length of the plate. In Figures 10, 11 and 12 I have shown the plate as being provided with a depending flange 14 opposite the depending flange 11 in close proximity to its adjacent side of the support. In this last form these two depending flanges may be shaped to snugly engage the opposite sides 95 of the support to keep the plate in a more rigid relationship to the support.

From the above description it will be seen that I am enabled to readily provide a replaceable stationary member for coaction 100 with the movable tension member, said replaceable member being preferably made of a greater wear resisting material than would

be feasible for the support, because of the expense incident thereto. It will furthermore be seen that these plates may be very easily and readily replaced at a slight expense.

5 Furthermore, it will be seen that these plates may be put in use in connection with the numerous tension devices of this character now in operation, even where the yarn contact surfaces of the supports have become 10 worn, thereby obviating the necessity of replacing the said supports.

15 It is evident that the several embodiments shown and described are only a few of many different forms which the tension might assume. It is also evident that various changes in the construction, form and arrangement of the several parts might be made without departing from the spirit and scope of my invention; hence, I do not intend to be limited 20 to the particular embodiments herein shown and described, but what I claim is:—

25 1. In a yarn tension device, a tension washer, a stationary support therefor having the usual yarn contact surface under said washer, and a replaceable non-yielding stationary wearing plate located upon said yarn contact surface for protecting the same from wear and for permitting the further use of the tension device, said plate having means 30 for preventing the accidental threading of the yarn underneath the plate.

30 2. In a yarn tension device, a tension

washer, a stationary support therefor having the usual yarn contact surface under said washer, and a replaceable non-yielding stationary wearing plate located upon said yarn contact surface for protecting the same from 35 wear and for permitting the further use of the tension device, said plate having a depending flange extending rearwardly from its leading-in end in close proximity to the adjacent side of the support for preventing the accidental threading of the yarn underneath the plate.

40 3. In a yarn tension device, a tension washer, a stationary support therefor having the usual yarn contact surface, and a replaceable non-yielding wearing plate located upon said yarn contact surface for protecting the same from wear and for permitting 45 the further use of the tension device, said plate having a depending flange extending rearwardly from its leading-in end and engaging its adjacent side of the support for preventing the accidental threading of the 50 yarn underneath the plate, the plate also having another depending flange engaging the opposite side of the support to keep the plate in a more rigid relationship to the support.

55 In testimony, that I claim the foregoing 60 as my invention, I have signed my name this 24th day of November, 1926.

JOHN O. McKEAN.
